Roland C. Sleight. INVENTOR:

BY
Hedden & Fairbanks ATTORNEYS.

UNITED STATES PATENT OFFICE.

ROLAND E. SLEIGHT, OF PHILADELPHIA, PENNSYLVANIA.

COLOR-MATCHING DEVICE.

Application filed May 13, 1925. Serial No. 29,893.

To all whom it may concern:

Be it known that I, ROLAND E. SLEIGHT, a citizen of the United States, residing at Philadelphia, in the county of Philadelphia and State of Pennsylvania, have invented a new and useful Color-Matching Device, of which the following is a specification.

My invention relates to a new and useful color matching device, particularly adapted for matching various colors and shades of inks, pigments, dyes or paints.

In ordering or selecting an ink, pigment, dye, or paint, to reproduce a given color or shade, either in a print, lithograph, or otherwise, it has heretofore been a rather difficult, delicate, tedious and time consuming task, accurately to match any particular shade of color. This is particularly true in matching inks or pigments with a given shade of color, as found for instance, in a finished picture, produced by printing, lithographing or any of the multi-color printing processes. This is particularly due to the fact that the colors or shades of various colors, as they appear in a print or lithograph, are not always, or are usually not, of solid shade, but appear rather as intermediate shades of the particular color or shade, depending upon the "strength" of the plate printed from, or the "strength" of the particular portion of the plate, as well as upon the shade of color used.

By my novel color matching scheme and device, I am enabled quickly and accurately to match any shade of color regardless of the intermediate shades of such shade of color, that happen to appear in the picture or print sought to be matched.

I accomplish the above ends by providing a novel color matching device, which may be a single sheet or a matching book, composed of a series of leaves, each representing a successive color and shade of color, in the color scale. Each leaf is provided with a suitable matching aperture, having an area immediately surrounding or adjacent to said aperture, colored preferably by some process of printing, in the "solid" shade, of the particular shade of color corresponding to that leaf or page. I further provide upon the same sheet, a second matching aperture, of suitable shape and size, preferably a somewhat elongated opening, and color a series of areas immediately surrounding or

adjacent to said elongated aperture, with a series of various intermediate shades, of the particular shade shown around the first aperture in solid, representing intermediate shades of the same shade of color, in varying "strengths" of the plate printed from.

I further provide a small colored area in the "solid" shade of the particular leaf or page, along one of the free edges of the leaf, preferably the edge of the leaf opposite the binding edge. This serves as a visible index to the particular shades and colors contained within the matching book.

For the purpose of illustrating my invention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1, represents a plan view of one leaf or page of my novel color matching device, partly finished, and embodying my invention.

Figure 2, represents a plan view of the same page, shown in Figure 1, completed in including the matching apertures.

Figure 3, represents a plan view of another leaf of my novel color matching device, corresponding to a different color.

Figure 4, represents a perspective view of my novel color matching book in the open position.

Figure 5, represents a perspective view similar to that shown in Figure 4, showing the manner in which the same is used.

Referring to the drawings, in which like reference characters indicate like parts, 1 designates a leaf or page of my novel color matching device corresponding to a black colored ink or pigment and designated for trade purposes by a suitable catalogue number or other indicia; in this particular instance "No. 131."

By means of such numbers, the ink or pigment corresponding to the particular leaf can readily be identified, thereby aiding in ordering such ink or color from the manufacturer. 2 designates the "solid" shade of

color, in the particular instance black; which is the particular shade of color printed from a plate of full strength. 3, 4, 5 and 6 designate a series of small contiguous areas of 5 "intermediate" shades of the same color or shade shown in the "solid" area 2, shown above. These areas are printed from portions of the plate, of less than full strength. 7 designates the index tab, or area, of the 10 same color or shade as the "solid" shade 2.

For the purpose of illustrating various shades of colors as well as various "intermediate" shades of each shade of color shown; I have resorted to a series of arbitrary cross-hatchings of various intensities, which for the purposes of description are assumed to represent the colors or shades, and their various intermediate shades designated by the names of colors printed on the particular leaf, as well as by the arbitrary catalogue numbers as shown.

In producing these leaves, the sheet is printed in a form shown in Figure 1, with a "solid" area 2, and the "intermediately" 25 shaded areas 3—6 inclusive, as well as the "solid" index area 7, preferably printed at one time and from the same plate. Thereafter the openings 8 and 9 are punched through, and the free edges 10 of the leaves 30 are cut, in such a manner as to draw the color of the areas 7, down over the edges of the leaves, so as also to produce a colored index edge 11, shown particularly in Figure 4. This is done by what is commonly known 35 in the art as "bleeding." While in the figures of the drawings I have shown only four contiguous areas 3, 4, 5 and 6 of the "intermediate" shades of the particular shade or color, it is to be understood that, that number 40 may be varied, as desired, although it has been found that four intermediate shades of any shade, ordinarily gives ample variation, so as to permit the quick and accurate matching of the "intermediate" 45 shades as found on prints, pictures or lithographs.

In Figure 3 I have illustrated another leaf 12, of my novel color matching book, also having the "solidly" shaded area 2, surrounding the aperture 8, and the four "intermediate" shades 3, 4, 5 and 6 along the elongated matching opening 9, as well as the "solid" colored index area 7. In this particular illustration I have represented a shade of blue, which is also designated by a particular catalogue number or other indicia 13.

The series of leaves corresponding to various shades of colors, such as the leaves 1, 12, 60 14 and 15, are then bound into suitable book form. By this means the free edges 10 of the leaves will be in vertical alignment with each other, so as also to align the exposed colored edges 11 of the index areas 7, as shown particularly in Figure 4. By this

means the book 16 can be opened to any desired shade or color, quickly and without paging through many leaves or pages. Having found the page or leaf corresponding to, or closely approximating the shade of color 70 desired, the picture, print or lithograph 17 is placed beneath the leaf or page in a manner shown in Figure 5, with a portion of the colored surface of said picture 17, which is to be matched, exposed to view through the 75 opening 8. By this means the shade of color can be matched, if such shade appears in the picture "solid." If the color to be matched does not appear in the picture in solid, but appears as an "intermediate" shade, namely 80 as a shade of color printed from a portion of the plate which is less than full strength, then such intermediate colored area is placed beneath the elongated matching opening 9 where such area can be compared quickly at 85 first sight, with any one of the various "intermediate" shades of the particular shade of color, which intermediate shades are so graded as to facilitate a quick comparison.

Since, from time to time, different new 90 shades of color are produced and new shades of ink or pigments are placed on the market, it is desirable to arrange the various leaves, such as 1, 12, 14 and 15, in a loose leaf folder such as 18, shown in Figures 4 and 5, instead of binding such leaves together in a permanent form. By this means a new leaf may be inserted into the book at any time, in its proper relative position with respect to the other shades already in the book, in case such new shade of ink or pigment is produced. In order more readily to adapt my novel matching sheets to the loose leaf folder 18, I may punch a plurality of small openings 19 along the binding edge 20 thereof, of suitable size and suitably spaced, to receive the rings 21 of the loose leaf folder 18.

It will now be apparent that I have devised a novel and useful color matching device which embodies the features of advantage enumerated as desirable in the statement of the invention and the above description, and while I have, in the present instance, shown and described a preferred embodiment thereof which will give in practice satisfactory and reliable results; it is to be understood that such embodiment is susceptible of modification in various particulars without departing from the spirit or scope of the invention or sacrificing any of its advantages.

Having thus described my invention, what I claim as new and desire to secure by Letters Patent is:—

1. In a color matching device of the character stated, a sheet having on one portion thereof a "solid" color, and on another portion thereof a series of "intermediate" shades of said solid color, adapted for comparison with a given colored surface of a desired 125

shade of ink printed from a plate of less than full strength, an edge of said sheet having a colored index area thereon.

2. In a device of the character stated, a sheet having a matched aperture there-through, a colored area on said sheet of a desired shade, adjacent to said aperture, and a colored index area on said sheet of the same shade adjacent to an edge of said sheet.

10 3. In a device of the character stated, a book composed of outer covers, a plurality of leaves or pages, a matching aperture through each of said leaves, a colored area of a desired color and shade adjacent to said aperture; and a colored indexed area of the same color and shade adjacent to the free edges of said pages.

15 4. In a device of the character stated, a flexible sheet, a "solid" matching aperture therethrough, a "solid" colored area of any particular color and shade adjacent to said aperture, an "intermediate" matching aperture through said sheet, and a plurality of graded "intermediate" shade areas adjacent

to said aperture, each of an "intermediate" shade of the color of the "solid" shade on said sheet.

25 5. In a device of the character stated, a book composed of outer covers, a plurality of leaves, a colored area on said leaves of a particular shade or color in "solid," a "solid" matching aperture through each of said leaves, an "intermediate" matching aperture through said leaves and a plurality of "intermediate" shade areas adjacent to said aperture, each of an "intermediate" shade of 30
35 said particular "solid" shade.

6. In a device of the character stated, a book composed of outer covers, a plurality of leaves, a colored area on each of said leaves of a particular shade in "solid," a "solid" matching aperture through each of said leaves, a plurality of "intermediate" shade areas, an "intermediate" matching aperture through said leaf, and an index 40
45 area of said "solid" shade adjacent to a free edge of said leaf.

ROLAND E. SLEIGHT.
